UNITED STATES PATENT OFFICE.

EDWIN FORREST, OF NEW YORK, N. Y.

PHOTOGRAPH.

1,257,492.

Specification of Letters Patent. Patented Nov. 2, 1920.

Application filed September 1, 1917. Serial No. 183,279.

To all whom it may concern:

Be it known that I, EDWIN FORREST, a citizen of the United States, residing at New York city, in the county of New York and State of New York, have invented certain new and useful Improvements in Phonographs, of which the following is a specification, reference being had therein to the accompanying drawing.

10 My invention relates to improvements in phonographs and has more particularly to do with means in combination with the box, cabinet or stand of a phonograph for developing and improving the sound properties.

15 Referring to the accompanying drawings, Figure 1 illustrates in perspective, with parts broken away, an application of my invention as applied to a phonograph adapted to be used upon a table. Fig. 2 is a front elevation partly in cross section, illustrating modifications and Fig. 3 illustrates a modified form of base.

20 The driving mechanism of the phonograph is suitably secured within the casing as indicated at 3' in Fig. 2 and rotates the disk 4 in the usual manner through the table 5 upon which the sound arm 6 is mounted and which is preferably of the construction set forth in my copending application, Serial No. 183,651. The lower part of the interior of the cabinet within which the motor driving mechanism is mounted it will be observed is formed substantially hemispherical as indicated at 7 and the sound arm 6 communicates through the base thereof by the tube 8 as shown, the sound waves striking upon the curved sound base 9 from which they rebound to the outside of the cabinet 10 through the fine screen or gauze 10 at the back of the grilles 11.

In the modification shown partly in cross section in Fig. 2 the tube or passage carrying the sound from the sound arm 6 is indicated by the reference character 8 and 45 delivers the sound upwardly through the sound base 9, the sounds striking upon the spherical surface 7 and rebounding as aforesaid. The sound reflecting surfaces may be curved or composed of a series of sections 50 tapering upwardly as shown or may comprise a series of composite surfaces, and of course various other changes may be made in the construction and arrangement of parts without departing from the spirit of the 55 invention as claimed.

I claim:

1. In combination with a phonograph, a pair of convex sound deflecting surfaces having their apexes opposed, and means for discharging the sound between said surfaces. 60

2. In combination with a phonograph, a pair of convex sound deflecting surfaces having their apexes opposed, and means for discharging the sound between said surfaces 65 by a tube from the sound producer extending to the apex of one of said surfaces.

3. In combination with a phonograph, a pair of convex sound deflecting surfaces having their apexes opposed, and means for 70 discharging the sound between said surfaces, and a clearance laterally entirely around the periphery of said surfaces for the escape of sound.

In testimony whereof I hereunto affix my 75 signature in the presence of two witnesses.

EDWIN FORREST.

Witnesses:

ANNA F. DUFFY,
THOMAS A. HILL.
